UNITED STATES PATENT OFFICE.

ABE KRAMER, OF DES MOINES, IOWA.

SAFETY-ENVELOP.

1,295,327.

Specification of Letters Patent. Patented Feb. 25, 1919.

Application filed April 20, 1918. Serial No. 229,867.

To all whom it may concern:

Be it known that I, ABE KRAMER, a citizen of the United States, and resident of Des Moines, in the county of Polk and State of Iowa, have invented a certain new and useful Safety-Envelop, of which the following is a specification.

The object of my invention is to provide a safety envelop of simple, durable and inexpensive construction.

More particularly it is my object to provide an envelop of the type which, by slight modification, may have a single safety element, or a double safety or protection element, or a triple safety or protection element.

With these and other objects in view my invention consists in the construction, arrangement and combination of the various parts of the device whereby the objects contemplated are attained, as hereinafter more fully set forth, pointed out in my claim and illustrated in the accompanying drawings, in which:

25 Fig. 1 shows a plan view of the inside of an envelop embodying my invention.

Fig. 2 shows a plan view of the back of the envelop in closed position.

30 Fig. 3 shows a plan view of a modified form of my invention with the flaps open.

Fig. 4 shows a plan view of the back of the envelop shown in Fig. 3.

35 Fig. 5 shows a view of the rear or back surface of another modified form of my envelop having the triple safety feature with the flaps open; and

Fig. 6 shows a plan view of the rear or back of the envelop shown in Fig. 5 closed.

40 In the accompanying drawings I have used the reference numeral 10 to indicate the side wings or flaps of an envelop of the kind embodying my invention.

Secured to the front of the envelop is what I will call a lower flap 11 having adhesive material 12 at its edge. In the flap 11 is cut spaced, alined slots 13 between which is formed a tongue 16 having adhesive material 12 on its inside surface.

45 At the top of the envelop is the upper flap 17 having a central projecting tongue 18. The flaps 17 and 18 are provided with adhesive material on their inside surfaces near their edges, as shown.

50 In the use of the envelop shown in Figs. 55 1 and 2, the lower flap 11 is folded over against the side 10 after the side wings have

been folded over to their positions shown in Fig. 1, and the adhesive material 12 on the edge of the flap 11 is moistened, so that the flap 11 will stick to the side wings 10. 60

As a matter of fact when the envelop is made the flap 11 can be sealed to the wings 10 by means of the adhesive material 12. When it is then desired to close the envelop with a letter or the like inside it, the tongue 16 is pulled out slightly and the flap 17 is folded over and the tongue 18 inserted through the slots 13 and the slot formed adjacent to the tongue 16. The adhesive material 12 on the tongue 16 may then be 70 moistened and the tongue 16 sealed to the tongue 18. The adhesive material on the tongue 18 and the flap 17 may be moistened before the envelop is closed, and by pressure the flap 17 may be sealed to the side wings 75 10 on the outer surface of the flap 11 and the tongue 18 may be sealed to the side wings 10 near the flap 11. The tongue 16 will also be sealed to the outer surface of the tongue 18. It will be seen that it would be impossible to open an envelop of the kind shown, 80 without leaving plain indication of the fact that the envelop had been tampered with.

In Fig. 4 I have shown a slightly modified form of the invention in which the reference 85 numeral 20 is used to indicate the side wings. The bottom flap 21 has at its upper edge near one end thereof a tongue 22.

The tongue 22 and the flap 21 near the edges thereof are provided with adhesive 90 material 12 similar to that already described. An upper flap 23 is provided.

The flap 23 has opposite the tongue 22 spaced slits 24 between which is a curved slot whereby there is formed a tongue 25. 95 The tongue 25 has adhesive material near its edge on its under surface. The flap 23 has at its outer edge near one end a tongue 26. The under surface of the flap 23 and tongue 26 near their edges are provided with adhesive material 12. The flap 21 is provided opposite the tongue 26 with slots 24 and a tongue 25 similar to those described in connection with the description of the flap 23. 100

105 It will be noticed that the tongues 22 and 26 are staggered with relation to each other, so that when the envelop, shown in Fig. 3 is completed, the flap 21 may be sealed to the side wings 20, and thereafter the flap 23 may be folded over and the tongue 22 inserted through the slots 24, whereby the tongue 25

is formed, while the tongue 26 may be inserted through the slot 24 in the flap 21 in the same way.

The completed envelop thus described is 5 shown in Fig. 4.

In Figs. 5 and 6 I have shown another form of my invention slightly different from the ones heretofore described.

In the form of the envelop shown in Figs. 10 5 and 6 there is a front portion having end wings 27 arranged to overlap each other when folded over the front portion. A lower flap 28 is provided with spaced pairs of slots 29. Arranged at right angles to each slot 24 15 is a pair of slots 30 between which is formed a tongue 31.

At the edge of the flap 28 at the middle thereof is a tongue 32. An upper flap 35 is provided and has spaced tongues 36 adapted 20 to enter the slots 29, spaced between the tongues so as to admit the tongue 32. The various tongues hereinbefore described are provided on their under surfaces with adhesive material 12 near their edges as are 25 the flaps 28 and 35.

In the completion of the envelop shown in Figs. 5 and 6, the lower flap is folded up and the upper flap is then folded over the lower flap with the tongues 36 inserted 30 through the slots 29. The tongue 32 engages the outer surface of the central portion of the flap 35 and is sealed thereto. It will be noted that the various tongues 18, 22, 26, 32 and 36 may be sealed to the outer surfaces of the opposite flaps without the use 35 of the slots if desired.

It will also be noted that in Figs. 1 and 2

I have shown an envelop with a single safety or protecting device. In Figs. 3 and 4 an envelop with a double safety protecting 40 means is shown, and in Figs. 5 and 6 an envelop with a triple safety or protecting means is shown.

It will be seen that with an envelop of this kind it would be impossible to get inside 45 the envelop without leaving evidence that the envelop had been tampered with.

The flap and tongues herein described may be made of double thickness to make 50 them stiff and easier to manipulate.

It may be noted that it would be easy to make an envelop of this kind the inside of the front of which, and the inside of the end flaps of which could be used for letter writing purposes. 55

I claim as my invention:

An envelop having a front portion, overlapping end wings folded over against said front portion, a lower flap and an upper flap, each of said flaps being provided with a tongue and with a slot, shaped to form a smaller tongue, the tongue of one flap being opposite the slot of the other flap, said tongues being provided with adhesive material on their inner surfaces, whereby the 60 tongue of one flap may be inserted through the slot in the other flap, and sealed to said end wings, whereby the flap formed adjacent to each slot may be sealed to the tongue of the opposite flap, and so that adjacent to 65 each end of the envelop each flap will be sealed to an end wing and to the other flap. 70

Des Moines, Iowa, April 15, 1918.

ABE KRAMER.
